UNITED STATES PATENT OFFICE.

ALBERT E. HUDSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

PRESS.

Application filed February 25, 1921. Serial No. 447,650.

To all whom it may concern:

Be it known that I, ALBERT E. HUDSON, a citizen of the United States, residing at Beverly, in the county of Essex and State of Massachusetts, have invented certain Improvements in Presses, of which the following description, in connection with the accompanying drawings, is a specification, like reference characters on the drawings indicating like parts in the several figures.

This invention relates to presses and more particularly to presses of the type employed in cutting sheet material by the use of freely movable dies.

15 One type of press which has given very general satisfaction in the art of cutting sheet material is that known commercially as the clicking machine. As shown in United States Patent No. 921,503, granted May 11, 20 1909, upon application of Arthur Bates, this machine comprises characteristically a work supporting bed of considerable area and a presser member having a presser surface of less area than the bed and mounted 25 at one end so as to be movable over the bed to cooperate with different areas thereof from one end of the bed to the other. The machine has proved so advantageous in the cutting of sheet material that its use has 30 been extended beyond that originally contemplated. Whereas as originally designed the machine was intended for the cutting of relatively thin sheet material, it is now also employed in the cutting of thick and heavy 35 sheet material and of fabrics piled in a multiplicity of layers.

It is an object of the invention to provide an improved press which, while especially applicable to heavy work, retains all of the 40 important principles of construction that contribute to the high efficiency and general desirability of the commercial clicking machine.

In the illustrative machine a movable 45 presser member is provided having integral trunnions for mounting the presser member on the frame of the machine. From another view point, the presser member and the post which supports it are exhibited as one, integral, strongly constructed member, capable 50 of forcing a die through the many thicknesses of work which can be interposed between the presser member and work supporting bed, without angular displacement 55 of the presser member. In other words, the

pressure applying surface of the presser member is maintained parallel with the surface of the bed during pressure applying operations, the result being perfect cutting of the material and greatly prolonged life 60 for the dies and the cutting block over previous records.

The invention contemplates also an improved mounting for the presser member whereby friction during reciprocation of the member is reduced thus lessening wear of 65 the parts and conserving power.

In order that the presser member may be moved over the work supporting surface of the bed with the minimum of effort on the 70 part of the operator, power means is provided for that purpose, important features of the invention residing in improved means for moving the presser member and particularly in the controlling means which enables 75 the operator to move the presser member with ease and dispatch to the desired location and to cause a pressure-applying movement of the presser member, upon proper manipulation of a single member. The construction of the means for moving the presser member laterally over the bed is 80 preferably such that the controlling means may be operated to disconnect the moving means from the presser member so that the latter may be moved directly by the hand 85 when so desired.

Other important features of the invention, including combinations of parts and details of construction, will be described in 90 the specification and pointed out in the appended claims.

In the drawings:—

Figure 1 is a view in side elevation and partly in section of a press embodying the 95 invention;

Fig. 2 is a top plan view partly in section of the power means for moving the presser member laterally of the bed;

Fig. 3 is a detail of the power means and 100 of the controlling means therefor in side elevation and partly in section;

Fig. 4 is a detail of the cable connection 105 between the presser member and the power means for moving the same;

Fig. 5 is a section through the upper end 110 of the post and the upper bearing for the same;

Fig. 6 is a broken-away sectional view taken along the line 6—6 of Fig. 5; and

Fig. 7 is a detail view of an anti-friction device taken along the line 7-7 of Fig. 6. In the illustrative machine the work is positioned for cutting operations upon a table or block 10 which is adjustable vertically in the frame 12 of the machine through the operation of screw threaded members in accordance with an old and well known arrangement. For co-operation with the work supporting bed 10 there is provided a presser member 14 which is movable toward and from the bed in pressure applying operations and also laterally of the bed in order that work may be operated upon wherever located on the bed. For supporting the presser member for rotation and also for reciprocation in the frame of the machine there is provided a post 16 which is receivable in bearings, one of which is indicated at 18 and is preferably integral with the frame of the machine. The other bearing is shown at 20 and in the preferred construction is adjustably mounted upon the upper end of the frame as will be herein-after described. As before stated, an important feature of the invention resides in the construction of the presser member and the post as a single integral member, which possesses the advantages of requisite strength and rigidity without undue weight. The improved construction also obviates certain of the defects and disadvantages of presses as heretofore constructed, which relate principally to difficulty in maintaining the presser arm rigid with the post and in fixed relation thereto. It will be readily understood that the frequent application of power to the outer end of the presser arm would result, in prior constructions, in loosening the connection between the presser arm and its supporting post. In those prior constructions wherein the presser member is yieldingly mounted so as to spring away from the bed, the dies are often forced into the block much deeper at one end than at the other, thus subjecting the dies to strains which not infrequently result in breakage of the latter and also damage to the cutting surface of the bed or cutting block. In the illustrative construction the presser member is maintained with its pressure applying surface parallel to the bed thus ensuring clean and perfect cutting of the material and removing the cause of much of the damage to dies and cutting blocks heretofore experienced during cutting operations. From another viewpoint, the combined presser arm and post may be regarded as a presser arm having integral trunnions 22, 24 which support the presser arm in the bearings 18 and 20, respectively. Extending through the power post 16 is a shaft 26 secured to the upper end of the post as shown in Fig. 5 and having its lower end operatively connected to the horizontal power shaft 28

through a pitman 30 pivoted to the shaft 26 at 32, the said pitman having a portion which surrounds an eccentric 34 on the shaft 28. As shown in Fig. 1, the shaft 28 is mounted in bearings in the bottom part of the machine frame and is provided with a power pulley 36 arranged to be connected with the shaft through clutch mechanism 38 which may be of any well known type of one revolution non-repeating clutch mechanism. Mounted in the upper portion of the frame is a lever 40 which is movable about a horizontal pivot to control the clutch 38 through the connecting rod 42, a single actuation of the manually operable lever 40 resulting in one pressure applying operation upon work positioned on the bed 10.

The power means for moving the presser member laterally along the bed 10 into and out of any selected position with reference to work supported on the bed comprises in the construction shown a horizontal shaft 44 (Fig. 2) which has attached fixedly to one end thereof a pulley 46. Surrounding the shaft 44 is a sleeve 48, in two parts to facilitate assembling of the sleeve on the shaft, and mounted in the bearings 50, 52, provided by a bracket 54 supported upon a relatively long pivot bar 56 provided with a suitable bearing in the frame of the machine. Secured to the sleeve 48 or integrally formed with a portion thereof is a pulley 58. Referring again to Fig. 1 it will be observed that in the illustrative construction the power pulley 36 has integrally formed therewith or securely attached thereto a couple of pulleys 60, 62 and extending from the pulley 60 to the pulley 46 is a cable 64 which is crossed intermediate of its length. A similar cable 66 connects the pulley 62 with the pulley 58 and since the power pulley 36 with the attached pulleys 60 and 62 is running continuously it follows that the shaft 44 and the sleeve 48 are also turning continuously. Due to the crossing of the cable 64 intermediate of its length, the pulley 46 is, however, turning in a direction opposite to that of pulley 58. Mounted rotatably upon an intermediate portion of the shaft 44 is a sleeve 68 to which is keyed a clutch member 70 having securely attached thereto a sprocket wheel 72 by means including a screw threaded bolt 74. Between one end face of the member 70 and the sleeve clutch member 76 is interposed a set of friction clutch plates 78 surrounded and retained in place by the flange portion 80 of the member 76. Upon moving the member 70 to the right in Figure 2, the said member is clutched to the sleeve 48 and caused to rotate with the sleeve as a source of power which is transmitted through the sprocket chain 82 which engages at one end with the sprocket 72 and with its other end the sprocket 84 on the worm shaft 86. Re-

Referring to the pivoting of the bracket 54 on the pivot rod 56, it should be pointed out that adjustment of the bracket toward and from the frame (Fig. 3) is secured by means of two set screws 85 and 87 (Fig. 2), one of which holds the bracket in adjusted position and the other of which is utilized to make the adjustment in a manner that will be well understood without further description. The purpose of the adjustment of the bracket toward and from the frame is to provide for proper tensioning of the sprocket chain 82. Movement of the member 70 to the left in Fig. 2 results in clutching the said member to the clutch member 88 which is pinned to the shaft 44 and is of the same general construction as the clutch member 76 in that it contains another set of friction plates 90 similar in all respects to the plates 78. When the member 70 is moved to the left as described it is clutched to rotate with the shaft 44 and hence the sprocket wheel 72 is then rotated in a direction opposite to that first described. For shifting the member 70 in opposite directions selectively at the will of the operator connections are provided between said member and the manually operable member 40 which is so mounted as to project into a position accessible to the operator standing at the front of the machine. In the illustrative construction, these connections comprise a vertical rod 100 mounted rotatably in a bearing 102 in a bracket 104 secured to the frame of the machine, a collar 106 pinned to the rod serving to limit movement of the rod in one direction with respect to its bearing and the connecting member 108 also pinned to the rod above the bearing 102 operating to limit movement of the rod in an endwise direction and furnishing the connection with the lever 40 by which the rod is rotated. At the lower end of the rod 100 and pinned thereto is a sleeve member 112 carrying arms 114 with inturned ends arranged in alignment with each other and carrying rolls 116 which are receivable in a circular slot 118 in the periphery of the member 70. It will be clear that the construction of the connecting member which operates to shift the member 70 in an endwise direction is such as to maintain connection with the member 70 while permitting rotation thereof in either direction. Referring to the construction illustrated in Fig. 3 it will be observed that the worm 124 which is securely attached to the shaft 86 is constantly in mesh with a worm gear 126 mounted for rotation upon the upper end of a shaft 128 and normally held to rotate with the shaft by means of a latch member in the form of a sleeve 130 having a projection 132 receivable in a recess 134 in the flange portion of the worm gear 126 and normally maintained in latched relation by the spring 136. It will be understood that the sleeve 130 is keyed to the shaft 128 as indicated at 138 (Fig. 1), the arrangement being such that the key holds the sleeve 130 to rotation with the shaft but permits it to slide endwise on the shaft into and out of latching relation to the gear wheel 126. Intermediate of the bearings 140, 142 for the shaft 128 is a drum member 144 to which the ends 146, 148 (Fig. 4) of the cable 150 are attached, the said cable intermediate of its ends being wound around a drum 152 integral with or securely attached to the post 16 which carries the presser member 14. In the illustrative construction the drum member 144 is mounted for rotation on the shaft 128 but is held frictionally for rotation with the shaft by means of a friction plate 154 which is keyed to the shaft 128 as indicated at 155, a circular plate 157 being mounted upon the hub of the plate 154 and being connected to the drum 144 by bolts 158. As shown, springs 156 are interposed between the heads of the bolts and the under surface of the plate 157, thus drawing the drum 144 and the plate 157 yielding toward each other and into contact with opposite sides of the friction plate 154, whereby the drum is held frictionally to the shaft 128. It will be understood that the bolts 158 cross the space between the drum 144 and the plate 157 outside of the periphery of the friction plate 154 so that the only connection between the drum and the friction plate is that established by contacting with the adjacent face of the friction plate.

Referring to Figs. 1 and 3 it will be seen that the starting lever 40 is pivoted by the rod 100 for lateral swinging movement, and also that the connecting member 108 between the rod and the lever 40 is provided with a pivoted bolt 170 which is horizontally arranged so that the lever may move in a vertical plane to control the clutch on the main shaft 28. As heretofore pointed out the rod 100 is oscillatable selectively in two directions in the same plane to shift the clutch member 70 on the shaft 44 and thus determine the direction of rotation of the presser member 14 over the bed 10. It will thus be clear that the lever 40 is a controlling lever for the power means which causes reciprocation of the presser member toward and from the work supporting bed and also for the power means which causes movement of the presser member into and out of selective operative positions over the bed. In addition the forward part of the lever 40 has another motion, that of axial rotation, provision being made for such movement as indicated in dotted lines in Fig. 1 of the drawings, wherein it will be observed that the forward end 172 of the rear portion 174 of the lever 40 is provided with a socket in which is receivable the rear end 176 of the forward

130

portion of the lever for axial rotation therein. Secured to the forward portion of the lever 40 is an arm 178 which extends substantially parallel with the general direction 5 of the lever 40 and which, in the normal position of the lever 40, is directly above the said lever. If, however, the forward portion of the lever 40 be turned on its own longitudinal axis through 90 degrees, the 10 projecting arm 178 is moved into a horizontal plane with the lever 40 and in its movement contacts with and actuates a lever 180 (Fig. 3) pivoted at 182 upon a bracket 184 extending from the frame of the machine. 15 The other arm 186 of the lever 180 is bifurcated and provided with rollers 188 (see Fig. 1) receivable in a circular slot 190 in the sleeve 130. As shown, the upper end of the arm 180 has a shallow groove or pocket 20 192 to receive the curved surface of the extension member or cam 178 whereby the said cam member is yieldingly retained in position through the action of the spring 136. When the lever 186 is actuated the sleeve 130 25 is lifted to withdraw the latched projection 132 from contact with the worm gear 126, thus disconnecting the worm gear from the shaft 128. This operation is necessary in order that the presser member 14 may be 30 moved by hand laterally over the work supporting bed and when it is desired thus to move the presser member the power means is disconnected as just described simply by rotating axially the forward portion of the 35 starting lever 40, the forked handle portion 194 on the lever 40 affording sufficient leverage to facilitate the rotation of the lever in the manner described. For moving the presser member by hand a handle 195 is preferably 40 provided at the outer end thereof (Fig. 1). A feature of the power means for swinging the presser member laterally over the work supporting bed is the provision therein 45 of the co-operating worm 124 and worm gear 126 through which power is transmitted to the upright shaft 128, the worm 124 operating to lock the gear wheel 126 in the position the respective parts have attained at the time of the disconnection of the clutch 50 70 from the power means represented by either of the pulleys 46, 58, this locking of the gear 124 and gear 126 serving to hold the presser member in the position to which it has been moved laterally of the bed. It is for the 55 purpose of lessening the shock on the gears just described that the friction plate 154 is provided to hold the drum member 144 operatively to the shaft 128 and hence at the termination of the movements of the gears 60 124, 126, the presser member may move slightly beyond the position that would otherwise be determined by the locking action of these gears. In order that the cable 150 may be adjusted properly with respect to its 65 connections with the drum member 144 and

the drum 152, the former drum is made in two parts as will be evident from an inspection of Fig. 4 and there is interposed between these parts a screw threaded member 196 having its ends mounted in rotatable 70 block members 198, 200, respectively, in such manner that upon rotation of the member 196, the two portions of the clutch member 144 may be caused to approach or recede from each other, thus loosening or tightening 75 up on the cable 150 in a manner that will be understood without further description.

From an inspection of Figure 1 of the drawings it will be understood that during 80 pressure applying operations upon the work supported on the bed, the presser member 14, because of the leverage involved, causes great lateral pressure upon the frame of the machine. In prior constructions this pressure was the cause of rapid wear in the 85 bearings and much waste of power in the operation of the machine. To overcome the disadvantages and defects of prior constructions there is provided, in the illustrative construction, an anti-friction device and a 90 bearing for the post which co-operate to remove practically all of the friction due to the lateral pressure on the bearings. Referring to Figs. 1, 5, 6 and 7, it will be seen that the upper end of the post 16 is provided 95 with a collar 17 having plates 210 secured in position by screws 212 and furnishing hardened surfaces for co-operation with anti-friction rollers 214 mounted in a cage 216 and contacting on the opposite side 100 with corresponding hardened surfaces on the plates 218 secured to the upper end of the frame 12. The cage referred to comprises side plates 220, 222 perforated to receive the ends of the rollers 214 and having 105 other perforations for receiving the ends of the bolts 224, 226 which hold the plates together. Preferably the lower end of the plate 210 is provided with lateral extensions 228 to engage beneath the lower end 110 of the plates 220, 222, thus supporting the cage 216 and maintaining it in proper operative position with the rolls engaging the faces of the plates 210, 218. It will be clear 115 from Fig. 5 that two cages 216 with their anti-friction rollers are provided between the frame 12 and the collar 17 at the upper end of the post 16, the cages being arranged at an angle of substantially 90 degrees from each other. As shown, the cages prevent 120 rotation of the collar 17 which becomes a bearing for the post 16 during rotation of the latter in the swinging movements of the presser member 14.

In order that the anti-friction rollers may 125 sustain the entire lateral pressure exerted upon the presser member 14 during a pressure applying operation, the upper bearing 20 for the post is preferably separate from the frame 12 and so mounted as to yield 130

slightly away from the front of the machine during a pressure applying operation for reasons that will be pointed out later. As shown the bearing 20 has arms 230 (Fig. 1), one on each side extending rearwardly in spaced relation and providing a support for the said bearing, the said arms being mounted on the upper end of the frame 12 by means of bolts 232 extending through 10 openings in the arms 230 which are slightly larger than the bolts so as to provide for slight relative movement between the arms and the bolts in a direction from front to rear of the machine. Extending through 15 the arms 230 in a direction at right angles to the bolts 232 are other bolts 234 which engage with the upright bolts 232 for the purpose of adjusting the bearing 20 laterally so as to position the post 16 accurately 20 with reference to the pair of anti-friction devices. At the rear end of the arms 230 are bolts 236, one for each arm which secures the arm to the frame of the machine but permits slight movement of the arm and 25 thus of the bearing 20, this movement being largely a movement of adjustment under the action of the bolts 238 in the downward extensions 240 of the arms. Preferably the adjustment of the bearing 20 is 30 such under the action of the adjusting members 238 that the post 16 is held in substantially vertical alignment within the bearings 18 and 20. However, as the fit of the post within the bearings cannot be tight 35 but must allow for a certain amount of movement, the upper bearing 20 is mounted as described to yield during a pressure applying operation so that the entire lateral pressure at the upper end of the post is 40 absorbed by the anti-friction devices.

Within the bearing 20 there is provided an anti-friction device comprising a collar 242 supported by the member 244 which is bolted to the upper end of the post 16. 45 Surrounding the collar 242 is a ring member 246 supported by the bearing 20 and providing, in conjunction with the collar 242, raceways for the anti-friction balls 248. As shown, particularly in Fig. 5, the upper 50 end of the shaft 26 is reduced to support a collar 254 which in turn supports one member 256 of a raceway for the anti-friction balls 258, a plate 260 serving to complete the raceway for the anti-friction rolls. 55 Above the member 244 which is bolted to the upper end of the post 16 there is located a nut 262 which is screw-threaded on the upper end of the shaft 26 and also pinned thereto. The construction just described 60 provides a connection between the upper end of the shaft 26 and the upper end of the post 16 such that upon reciprocation of the shaft 26, the post is also reciprocated, the connection being such moreover that the 65 post may rotate with respect to the shaft so

that the presser member may move laterally over the work supporting bed while the shaft 26 remains stationary.

In the operation of the machine the sheet material which is to be cut is placed upon the work supporting bed 10, the presser member at the time being displaced so as to uncover the bed. When a die has been properly positioned on the work the presser member 14 is caused to move into place above the die by proper manipulation of the lever 40. It will be understood that the lever 40 is moved laterally in the direction it is desired that the presser member should move and when the presser member has reached a proper position above the die pressure on the lever 40 is discontinued so that the power means is no longer operative to move the presser member, whereupon the presser member stops practically instantly in the selected operative position. In order words, upon disconnection of the power means for moving the presser member the latter does not continue to move under its momentum as in prior constructions but is held in the selective operative positions through the locking action of the worm 124 and worm gear 126 as fully set forth in the foregoing description. As soon as the presser member has reached operative position above the die the lever 40 is depressed, thus tripping the clutch on the main shaft 28 and initiating a pressure applying operation by which the die is forced through the work. At the completion of a cutting operation the lever 40 is moved in one direction or the other laterally of the bed to uncover the die and as much of the work as it is desired to inspect previous to repositioning the die. Should it be desired to move the presser member by hand the forward part of the starting lever 40 is rotated in the manner described to cause a disconnection of the worm and worm gear from the presser member and hence the latter may be easily moved directly by the hand of the operator. This may be a desirable method of moving the presser member when sheet material uniform in its essential characteristics is being operated upon, in which case the die or dies may be placed successively in close relation so that the presser member is moved but a short distance between cutting operations. If, however, sheet material such as leather, either skins or hides, is being operated upon the dies must be located after careful inspection of the work and according to a plan which must be carefully thought out and which varies for each skin or hide being cut. In work of this kind the presser member is moved through relatively greater distances than is the case in cutting operations on other sheet material, such as fabrics, and hence the power means for moving the presser member is most advanta- 120 125 130

geous and adds greatly to the efficiency of both the operator and the machine. Because of the strong construction of the presser member and the novel arrangement of its bearings, the presser member is maintained constantly with its pressure applying face in parallel relation to the bed and hence cutting operations on the sheet material are characterized by clean and perfect cutting without injury to the dies and with the minimum of wear on either dies or cutting bed.

Having thus described the invention, what is claimed as new and desired to be secured by Letters Patent of the United States is:

1. In a machine of the class described, a work supporting bed and a presser member relatively movable toward and from each other in pressure applying operations, and a post for supporting the presser member for swinging movement laterally over the bed, the said post being integral with the presser member and having trunnions mounted in bearings on the frame of the machine.

2. In a machine of the class described, a work supporting bed and a presser member relatively movable toward and from each other in pressure applying operations, said presser member having trunnions integral therewith for mounting the presser member in bearings on the frame of the machine.

3. In a machine of the class described, a work supporting bed and a presser member relatively reciprocable toward and from each other in pressure applying operations, and a post for supporting the presser member rotatably in bearings on the frame of the machine, said post and presser member being in the form of a single integral member.

4. In a machine of the class described, a work supporting bed and a presser member relatively reciprocable toward and from each other in pressure applying operations, a post formed integrally with the presser member for supporting the latter in the frame of the machine, and a member connected to the upper end of the post for reciprocating the presser member to effect pressure applying operations.

5. In a machine of the character described, a work supporting bed, a presser member movable laterally over the bed into and out of operative positions with respect to work on the bed and also movable toward and from the bed in pressure applying operations, a post for supporting the presser member, and an anti-friction device between the upper end of the post and the machine frame and arranged to take the lateral thrust of the presser member during pressure applying operations.

6. In a machine of the character described,

a work supporting bed, a presser member movable laterally over the bed into and out of operative positions with respect to work on the bed and also movable toward and from the bed in pressure applying operations, a post for supporting the presser member, bearings for the post on the frame of the machine, the upper bearing being movable on the frame, and an anti-friction device between the upper end of the post and the frame of the machine arranged to take the lateral thrust of the presser member during pressure applying operations, the construction and arrangement being such that the upper bearing moves to permit the anti-friction device to absorb completely the described lateral thrust.

7. In a machine of the character described, a work supporting bed, a presser member movable laterally over the bed into and out of operative positions with respect to work on the bed and also movable toward and from the bed in pressure applying operations, a post for supporting the presser member, bearings for the post on the frame of the machine, the upper bearing being movably mounted on the frame, and a member slidably attached to the upper end of the post and provided with anti-friction rolls interposed between said member and the frame of the machine.

8. In a machine of the class described, a presser member and a work supporting bed relatively reciprocable toward and from each other in pressure applying operations, power means for moving the presser member laterally over the work supporting bed into and out of selected operative positions with respect to work on the bed, power means for causing relative reciprocation of the presser member and bed, and controlling means for both the power means comprising a lever movable in one plane for causing operation of the first-mentioned power means and movable in another plane for controlling the other power means and movable in another way for disconnecting the first-mentioned power means from the presser member.

9. In a machine of the class described, a presser member and a work supporting bed relatively reciprocable toward and from each other in pressure applying operations, power means for moving the presser member comprising a worm gear operative to hold the presser member in the position to which it has been moved in the rotation of said gear, and a manually controllable lever for causing the operation of the power means and for disconnecting the power means from the presser member.

10. In a machine of the class described, a presser member and a work supporting bed relatively reciprocable toward and from each other in pressure applying operations,

power means for moving the presser member laterally over the work supporting bed comprising a worm gear, a friction plate driven indirectly by said gear, and operating connections between the friction plate and the presser member.

11. In a machine of the class described, a presser member and a work supporting bed relatively reciprocable toward and from each other in pressure applying operations, power means for moving the presser member laterally over the work supporting bed into and out of selected operative positions with respect to work on the bed, power means for causing relative reciprocation of the presser member and bed, and controlling means for both the power means comprising a lever movable in one plane for causing operation of the first-mentioned power means and movable in another plane for controlling the power means and axially rotatable for disconnecting the first-mentioned power means from the presser member.

12. In a machine of the class described, a work supporting bed, a presser member movable toward and from the work supporting bed and also laterally over the bed into and out of selected operative position, power means for moving the presser member laterally of the bed having parts constructed to hold the presser member in the position to which it has been moved by said power means, starting means for controlling the power means comprising a manually operable lever movable in the direction it is desired to move the presser member, and connections between the lever and the power means operable by the lever for disconnecting the presser member from said parts of the power means.

13. In a machine of the class described, a work supporting bed, a presser member movable toward and from the work supporting bed and also laterally over the bed into and out of selected operative position, power means for moving the presser member laterally of the bed constructed to hold the presser member substantially in the position to which it is moved by operation of said power means, and starting means for controlling the power means comprising a manually operable lever movable in a horizontal plane to cause lateral movement of the presser member and also movable to cause disconnection of the power means from the presser member so that the latter may be readily moved by hand.

14. In a machine of the class described, a work supporting bed, a presser member movable toward and from the work supporting bed and also laterally over the bed into and out of selected operative position, power means for moving the presser member laterally of the bed, starting means for controlling the application of power to the

presser member comprising a manually operable lever movable in opposite directions in the same plane for causing the power means to swing the presser member selectively in either direction over the bed and axially rotatable to cause disconnection of the power means from the presser member so that the latter may be readily moved by hand.

15. In a machine of the class described, a work supporting bed, a presser member movable toward and from the work supporting bed and also laterally over the bed into and out of selected operative position, power means for moving the presser member laterally of the bed comprising a co-operating worm and gear, a shaft upon which the gear is rotatably mounted, a member for connecting the gear to the shaft, connections from the shaft to the presser member for moving the latter in either direction over the bed, starting means for controlling the application of the power means to the presser member comprising a manually operable lever movable to control the power means and also to cause disconnection of the said gear from the shaft whereby the power means is disconnected from the presser member and the latter may be readily moved over the bed by hand.

16. In a machine of the class described, a work supporting bed, a presser member movable toward and from the work supporting bed and also laterally over the bed into and out of selected operative position, power means for moving the presser member laterally of the bed comprising co-operating worm and gear members, a shaft to which the gear may be operatively connected, and a cable connection between the shaft and the presser member arranged to permit of lost motion between the shaft and the presser member, the construction and arrangement being such that the presser member may be moved to selected position and held in that position through the normal locking operation of the worm and gear.

17. In a machine of the class described, a work supporting bed, a presser member movable laterally over the bed into and out of selected operative position, power means for moving the presser member laterally of the bed, starting means for controlling the power means comprising a manually operable lever movable in the direction it is desired to move the presser member, and connections between the lever and the power means operable upon axial rotation of the lever for disconnecting the power means from the presser member.

18. In a machine of the class described, a work supporting bed, a presser member movable laterally over the bed into and out of selected operative position, power

means for moving the presser member laterally of the bed, and starting means for controlling the power means comprising a manually operable lever rotatable axially to cause disconnection of the power means from the presser member so that the latter may be readily moved by hand.

19. In a machine of the class described, a work supporting bed, and a presser member relatively movable toward and from each other in pressure applying operations, the presser member being movable laterally over the bed into and out of selected operative position; power means for moving the presser member laterally of the bed, starting means for controlling the application of power to the presser member comprising a manually operable lever movable in opposite directions in the same plane for causing the power means to swing the presser member selectively in either direction over the bed and movable otherwise to cause disconnection of the power means from the presser member so that the latter may be readily moved by hand.

20. In a machine of the class described, a work supporting bed and a presser member relatively movable toward and from each other in pressure applying operations, the presser member being movable laterally over the bed into and out of selected operative position, power means for moving the presser member laterally of the bed comprising a co-operating worm and gear operatively connected to the presser member for moving the latter in either direction over the bed, starting means for controlling the application of the power means to the presser member comprising a manually operable lever movable to control the power means and also to cause disconnection of the worm and gear from the presser member so that the latter may be readily moved over the bed by hand.

21. In a machine of the class described, a work supporting bed, a presser member movable laterally over the bed into and out of selected operative position, power means for moving the presser member laterally of the bed comprising co-operating worm and gear members which operate to prevent movement of the presser member independently of the power means, and a yielding connection between the worm and gear members and the presser member, the construction and arrangement being such that the presser member may be moved to selected position and held in that position through the normal locking operation of the worm and gear.

22. In a machine of the character described, a work supporting bed, a presser member movable laterally over the bed into and out of operative positions with respect to work on the bed and also movable toward and from the bed in pressure applying op-

erations, a post for supporting the presser member, a bearing for the lower end of the post, and a movable bearing for the upper end of the post designed to hold the post normally in vertical position and movable during a pressure applying operation so that the lateral thrust of the presser member may be absorbed by the frame of the machine.

23. In a machine of the character described, a work supporting bed, a presser member movable laterally over the bed into and out of operative positions with respect to work on the bed and also movable toward and from the bed in pressure applying operations, a post for supporting the presser member, a bearing for the lower end of the post, and movable and fixed bearings for the upper end of the post.

24. In a machine of the character described, a work supporting bed, a presser member movable laterally over the bed into and out of operative positions with respect to work on the bed and also movable toward and from the bed in pressure applying operations, a post for supporting the presser member, a bearing for the lower end of the post, a movable bearing for the upper end of the post, and a second bearing for the post at the upper end thereof fixed against movement in a direction away from the presser member.

25. In a machine of the character described, a work supporting bed, a presser member movable laterally over the bed into and out of operative positions with respect to work on the bed and also movable toward and from the bed in pressure applying operations, a post for supporting the presser member, a bearing for the lower end of the post, a movable bearing for the upper end of the post, a second bearing for the upper end of the post fixed against movement in a direction away from the presser member, and anti-friction means between the post and the fixed bearing.

26. In a machine of the character described, a work supporting bed, a presser member movable laterally over the bed into and out of operative positions with respect to work on the bed and also movable toward and from the bed in pressure applying operations, a post for supporting the presser member, a bearing for the lower end of the post, a movable bearing for the upper end of the post designed for rotatably supporting the post, and a bearing at the upper end of the post for supporting the latter during vertical reciprocation thereof constructed to absorb the lateral component of the thrust on the presser member.

27. In a machine of the character described, a work supporting bed, a presser member movable laterally over the bed into and out of operative positions with respect to work on the bed and also movable toward

and from the bed in pressure applying operations, a post for supporting the presser member, a bearing for the lower end of the post, a movable bearing for the upper end 5 of the post designed for rotatably supporting the post, a second bearing for supporting the

post during vertical reciprocation thereof, and anti-friction means in the last named bearing.

In testimony whereof I have signed my name to this specification.

ALBERT E. HUDSON.
